UNITED STATES PATENT OFFICE

2,425,441

MECHANICALLY DRIVEN BOAT

Leo L. Riley, Redondo Beach, Calif.

Application September 28, 1944, Serial No. 556,224

6 Claims. (Cl. 115—35)

1

This invention relates to a mechanically driven boat propeller and to means for mounting and dismounting said propeller.

Among the objects of the invention are: To provide a propeller structure which may be more conveniently attached to boats already made, but not having been built with a view to providing them with mechanically driven propellers; to provide a special mounting means for such a propeller which includes a water-tight fitting through the bottom of the boat; to provide in combination with such a propeller and said mounting means therefor, a tool which may be efficiently utilized both to put the propeller into its operative position in relation to its said mounting means and to remove the propeller from its mounting means; to provide an improved means for regulating the direction in which the axis of the propeller extends in relation to the length of the boat thereby utilizing the propeller as a means for steering the course of the boat; and to provide an improved steering, clamping and mounting means for holding the propeller in place in a water-tight manner with the power conveying means therefor extending through an aperture in the bottom of the boat upon which the propeller is mounted.

A more specific object of the invention is to provide, in combination with an annular member fitted into an opening in the bottom of a boat and furnished with elastic integral packing means; a propeller-carrying tube insertable through and fitting within said annular member, and a tool constructed and arranged to draw said tube into its operative position within said annular member in such a manner as not to disengage said packing.

Other objects, advantages and features of invention will hereinafter appear.

Referring to the accompanying drawings which illustrate what is at present deemed to be a preferred embodiment of the invention,

Fig. 1 is a vertical mid-section of the propeller mechanism showing the same in its operative position upon a boat, a fragment of the hull of which is included in the view. Parts of the structure are broken away and other parts are broken out in order to contract the view.

Fig. 2 is a partly elevational and partly sectional view of the propeller in its operative position showing the same on a smaller scale, this view also showing the use of a special tool provided for the purpose of mounting and demounting the propeller.

2

Fig. 3 is a vertical mid-section of the mounting and demounting tool separately shown.

Referring in detail to the drawings, the power transmitting means for the propeller passes through a tubular member 10 fitted within a suitable opening therefor in the boat's bottom 11 and provided with an external annular flange 10a which is drawn upwardly against the boat's bottom by an annular member or collar 12 which is screwed on said member 10, as shown, thereby holding upright the assembly 13. Packing units 14 and 15, respectively located above and below the boat bottom surround a sleeve 16 fitted rotatively within the tube 10.

15 A shaft 17 is rotatably mounted within said sleeve 16 in an internally spaced relation to its inner surface, being surrounded in this position by a roller bearing 18 located within the upper end portion of the sleeve 16, and a lower bearing 19 located in the lower end portion of said sleeve, each end of the sleeve being internally recessed, as shown, in order to provide seats in which said bearings are secured by a friction tight fit. A bevel gear 20 secured to the lower end of said shaft 17 meshes with a like bevel gear 20a at the power transmitting end of a propeller shaft 31, while a bevel gear 21 secured to the power receiving end of shaft 17 by a nut 21x meshes with a like gear 21a of the driving means.

20 The gears 20 and 20a are contained within a housing 23 which is adjustably secured to the lower end of the sleeve 16, said housing being provided with an upwardly directed shank portion 23a which screws onto the lower end of the sleeve 16 and is locked to it by means of a collar 24 and set screws 25 and 26. The opposite, horizontally directed end portion of the housing 23 has screwed into it an externally threaded sleeve member 27 which is adjustably locked into position by a collar 28 and set screws 29 and 30. The propeller shaft 31 which has secured to it the aforementioned gear 20a, is secured within said sleeve member 27, as shown, together with an antifriction bearing 32, bearing sleeve 33, packing gland 34 and thrust collar 35. The propeller 36 is secured onto said shaft 31 by suitable splines 36a, as shown.

25 The special nuts 37, 38 and 39 are designed so as to take up the packings 14, 15 and 34 respectively, the nut for the latter bearing being provided with a set screw 39a. The nut 24a and set screw 25a clamp the nut 38 in adjusted position.

30 A sprocket wheel 40 is secured on the sleeve or tube 16 just above the nut 37, as shown, with a running fit in relation to said nut, being fixed to

35

50

said sleeve by a set screw 41. Sleeve 42 is mounted upon the sleeve 16 above the wheel 40 and supports the housing 22, an antifriction bearing 43 being provided between said sleeve and housing as shown. A lock collar 44 is mounted upon the sleeve 42 and is held in adjusted position by set screw 46, and a set screw 45 secures the bearing 43 in operative position between said sleeve 42 and housing 22, as shown. A retaining collar 43a is secured to the sleeve 16 and rides on the bearing 43.

The packing gland nut 37 and the ball bearing collar 42 are vertically spaced apart the proper distance to provide between them a vertically extending space within which the steering wheel 40 has a working fit, this arrangement partly enclosing said steering wheel and also aiding in keeping foreign matter from getting in around the turnable tube to which said wheel is attached.

The shaft 50 is secured to the motor or engine shaft 51 by a collar 52 furnished with set screws 52a and 52b as shown. The gear 21a is secured to said shaft 50. A sleeve 53 projects horizontally from the housing 22 as shown and is adjustably locked into position by a collar 54 and set screws 55 and 56. Antifriction bearings 57 and 57a are positioned between the shaft 50 and sleeve 53 as shown. The outer end of said sleeve 53 is rigidly supported by a standard 58 and set screw 59.

To dismount the propeller unit 16 from the standard assembly 13 a special tool 61 is designed, which comprises a cylindrical sleeve 63 carrying at its lower end an annular member 62 to fit down through and hold assembly 13 in place, including the packings 14 and 15, which would otherwise collapse if made of the soft compressible type and not internally supported.

The outside diameters of the sleeve 16 and adapter assembly 61 are the same, hence when these parts are axially abutted against each other an unbroken sliding surface results in the operation of drawing sleeve 16 down through the surrounding parts when it is necessary to remove the unit 13 for repairs.

Member 61 carries at its lower end an annular adapter 62 fittable within sleeve 63 as shown in Fig. 2, and has a guide bearing 64 to receive the threaded stem of the shaft 17. A shaft 65 is slidably fitted into the bore 66 at the upper end of said sleeve 63, and has a head 67 screwed onto its opposite end with a jam fit at 68. Said head 67 has a taper 69 to enable the operator to pull a cable 70 through the passages 64 and 66, said cable being connected to an eye part 71 of the shaft 65.

In order to install the tool 61 in place of the assembly 13, the nut 21x (see Fig. 1) and adjacent gear 21 are removed from the upper end of the shaft 17, and the tool 61 is then secured to the diametrically reduced threaded upper end 73 of said shaft shown in Fig. 2. Preparatory to removing said nut 21x, the housing 22 together with the standard 58 and intervening parts 50 and 53 are first removed, this being accomplished by first loosening set screws 45 and 46 and then screwing down vertically the lock nut or collar 44, it is then possible to rotate the sleeve 42 in the direction required to force the housing 22 upwardly until it is detached.

A tapered or frusto conical face 75 is provided within the upper part of the sleeve-like tool 63 to assist in aligning with and assembling into it the parts with which it cooperates. The cable

70 pulls shaft 65, head 67, adapter 62 and assembly 16 in place when that operation is necessary, for example, after repairs have been made.

It will be seen that by retaining the assembly 13 in position in the hull of the boat, said assembly extending above the water level 16, the propeller driving assembly 16 may be lowered into the water by cable 70 and fished out of the water, away from the boat; and the assembly operation is similarly made by dropping cable 70 (with its connected member 61 resting upon the shoulder 71, see Fig. 2). The shaft 65 and cable 70 then pass through sleeve 63 in assembly 13 and are connected to sleeve 16 and propeller 36, which are then lowered into the water by holding to the assembly 16 a suitable auxiliary cable hitch (not shown) and pulling assembly 16 back into place in assembly 13, and making final connections with members 58, 53, 50, 21, 44, 45 and 46. By using the tool assembly 63 in the manner just described the propeller can be repaired without drydocking the boat.

It will be seen that the member 10 forms the outer part of a tubular structure which is insertable upwardly through an opening provided therefor in the bottom of a boat. Also that the water tight housing 23 forms a part of a fitting having a horizontally directed extension to support the propeller shaft 31. The housing 22 carried by the upper part of the tubular structure houses the gearing which operatively connects the vertical power transmitting shaft 17 with the primary power transmitting shaft 50.

I claim:

1. In a structure of the kind described, an annular member fittable within an aperture in the bottom of a boat, a tube insertable through said annular member to support a propeller below the boat, power transmitting means for the propeller extending through said tube, and a tool having an end portion fitting within said tube with a working fit and connectible with an end portion of said tube to pull the latter up into an operative position within said annular member after the latter has been put into place within the aforesaid aperture.

2. The subject matter of claim 1, and said tool having an imperforate cross sectional structure thus adapting it to serve as a closure for the aperture through said annular member when the aforesaid tube has been removed.

3. In a structure of the kind described, an annular member fittable within an aperture in the bottom of a boat, a tube insertable through said annular member to support a propeller below the boat, said tube having a turnable working fit within said annular member, at least one packing gland around said tube containing a compressible packing to contact with said tube, and an elongated cylindrical tool connectible with said tube to draw it upwardly into said annular fitting to an operable position therein, said tool while within said annular member, serving to maintain said packing in an intact condition.

4. The subject matter of claim 3, and said tool having the same external diameter as said tube so that when connected with said tube it forms a smooth cylindrical continuation of the latter.

5. In a structure of the kind described, an annular fitting mountable in an opening in the bottom of a boat, a tubular structure insertable upwardly through said fitting, a water tight packing means carried by said fitting within which said tubular structure is turnable, a propeller carried by said tubular structure below said fitting, a

power transmitting shaft for said propeller extending through said tubular structure, bearings carried by said tubular structure and rotatably supporting said shaft, and a tool insertable in a downward direction through said annular fitting and connectable with said tubular structure to draw the latter upwardly into a position for having operating means within the boat connected to it.

6. A demountable propeller assembly for boats comprising a tubular structure insertable upwardly through an opening therefor in the bottom of a boat, said tubular structure including within it a longitudinally extending turnable tube, propelling means carried by the lower end portion of said tube, driving means for said propelling means extending through said tube, a wheel secured to and surrounding the said tube to co-operate with a power transmitting steering connection, a packing gland structure surrounding said tube to prevent leakage therearound through the bottom of the boat, said gland structure in-

cluding an apertured packing nut surrounding said tube in an overlying relation to the packing, and a bearing structure for the tube, said bearing structure including a supporting collar surrounding said tube and spaced sufficiently above said packing nut to provide between it and the latter a vertical space wherein said wheel has a working fit.
